EYE BOLT

Kenneth R. Mills, Gary, Ind., assignor to Screw & Bolt
Corporation, a corporation of Pennsylvania

Filed Sept. 21, 1962, Ser. No. 71,793

Term of patent 14 years

(Cl. D54—11)

Fig. 1

Fig. 2

Fig. 3

Fig. 4

FIG. 1 is a top plan view of an eye bolt, showing my
new design;

FIG. 2 is a front elevation thereof;

FIG. 3 is a side elevation; and

FIG. 4 is a sectional view along the line 4—4 of FIG. 2.

I claim:

The ornamental design for the eye bolt, as shown.
